UNITED STATES PATENT OFFICE.

HALBERT K. HITCHCOCK, OF PITTSBURGH, PENNSYLVANIA.

METHOD OF AND APPARATUS FOR APPLYING FINELY-DIVIDED MATERIAL TO GRINDING AND SMOOTHING MECHANISM.

1,311,519.

Specification of Letters Patent. Patented July 29, 1919.

Application filed August 9, 1915. Serial No. 44,624.

To all whom it may concern:

Be it known that I, HALBERT K. HITCHCOCK, a resident of Pittsburgh, in the county of Allegheny and State of Pennsylvania, have invented a new and useful Improvement, 5 in Methods of and Apparatus for Applying Finely-Divided Material to Grinding and Smoothing Mechanism, of which the following is a specification.

This invention relates to method and apparatus for handling, grading and applying finely divided abrasive material to grinding machines; such as sand or other abrading material to apparatus for grinding or 15 finishing plate glass.

The invention relates to that class of methods and apparatus for grading abrasives and applying the same to grinding machines wherein finely divided abrasive material, such as sand, is separated into grades of different sizes while in suspension in a liquid, such as described in my Patent No. 934,441, September 21, 1909, and which abrasive material while in suspension in the liquid is circulated repeatedly from the grading vessel to the grinding machine and back again, as described in my Patents No. 934,612 of September 21, 1909, and Nos. 1,056,415 and 1,056,416 of March 3, 1913, 25 and is an improvement upon the invention described and claimed in my application for method of applying abrasives to grinding machines, filed December 13, 1913, Serial No. 806,594.

One object of the invention is to provide a method and apparatus which produces in a single grading vessel a cleaner and more accurate separation or classification of the different grades of abrading material, which 35 also produces a denser mixture of the abrading material with the liquid in which it is suspended, and in which the grading operation is carried on under uniform conditions, with the production of sharply differentiated grades of material which are maintained at the various levels in the grading vessel, as a consequence of which contamination of one grade by particles from any other grade is largely avoided, the product 45 is improved, and more efficient results are secured, and at the same time the apparatus necessary for carrying out the method is simplified and the space required for its installation reduced.

A further object of the invention is to provide a method and apparatus whereby a dense mixture of the abrading material and liquid, especially of the finer grades, is secured by eliminating from the various levels in the grading vessel the superfluous liquid, 55 but retaining in said vessel the abrading material at said levels, so as to maintain a sufficient supply of the finer grades in suspension in a single vessel without the necessity of collecting and settling them in a separate vessel, thereby securing more rapid and efficient operation of the apparatus during finishing, and enabling the grinding and finishing operations to be carried out more economically, with less liquid, less handling of the material, in a shorter time and with as simple an apparatus as possible.

A further object of the invention is to provide a method and apparatus whereby a dense mixture of the abrading material suspended in a liquid is produced and maintained in the grading vessel, the several grades being uniformly distributed at various levels in said vessel, so that the operator can always rely upon the character of 65 each grade of abrading material at the various levels in the grading vessel, and in which the density of the mixture in the vessel is constantly indicated to the operator so that he will detect otherwise imperceptible 75 changes therein and can select the proper level from which to withdraw sufficient abrading material of the proper size for every stage of the grinding and finishing operation.

Further objects of the invention are in part obvious and in part will appear more in detail hereinafter.

In the grinding and smoothing of plate glass, and other surfaces where abrasive material is supplied, it has been found that it is highly desirable to have the abrasive supplied at any one time as nearly uniform in size as possible. The harmful effects of improperly graded material are apparent even 85 during the rough or coarse grinding, in which case if finer material is mixed with the coarse, it interferes with the most effective grinding action because to the extent that it displaces coarse material it decreases 95 the total grinding action, and is also wasteful of abrasive material because such finer particles are being reduced to a still finer

2 condition without producing any grinding effect. But it is during the stages of finer grinding that the effects of non-uniform grading are most harmful, as any coarse 5 material mixed with the finer material produces crushes or sand holes in the surface being ground, thereby necessitating further grinding to take out such rough ground spots and greatly delaying the final finish- 10 ing, or if not done the finished product is of an inferior quality.

In my prior application, Serial No. 806,594, before referred to, I have described and claimed one method for overcoming 15 these harmful effects by more accurate grading or classification of the material in the grading vessel and the rapid introduction of the coarse or unused sand or other abrad- 20 ing material in a single batch, or at least 25 rapidly during the early stages of the rough grinding, and in any event completing the introduction of the coarse abrasive material prior to the completion of the rough grind- 30 ing or facing and the beginning of the smoothing or finishing operation. The effi- 35 ciency of the system described in said ap- plication has so materially reduced the time of the facing and finishing operations and has so reduced the total quantity of new 40 abrasive material for each side of glass that every particle of fine sand produced during the rough grinding operation must be con- served in order to furnish a sufficient supply of the finer grades for the finishing opera- 45 tion. The finishing operation is also more advantageously conducted when the mix- 50 ture of abrading material with the liquid has a certain density, which density is greater than that ordinarily found in any 55 single grading apparatus.

The present invention is intended to se- 60 cure the beneficial results above specified and to also provide a method and apparatus whereby all of the abrasive material, both 65 the original supply and the used material, is graded or regraded under uniform con- 70 ditions and in a manner to collect in the up- 75 per portion of the grading vessel all of the finer abrading material produced during 80 the grinding operation, which material is 85 condensed or thickened by elimination of the surplus water at various levels in the 90 grading vessel, thereby enabling the grind- 95 ing and finishing operations to be carried 100 out with a minimum quantity of abrading 105 material, but nevertheless insuring a suffi- 110 cient supply of the finer grades for the 115 finishing operation, so that the entire opera- 120 tion can be carried out more economically, 125 with less liquid, less handling of the mate- 130 rial and with the simplest form of appa- ratus.

Various forms of apparatus are suitable 135 for carrying out the method. In the ac- 140 companying drawings, one arrangement of

suitable apparatus is shown, but it is under- 145 stood that this is merely illustrative and does not limit the invention.

In the drawings, Figure 1 is a plan view 150 of the apparatus, the dehydrating cones and gutter being omitted for clearness of illus- 155 tration; Fig. 2 is an elevation thereof, the sump being shown in section; Fig. 3 is a 160 sectional elevation of the grading vessel taken on the line 3—3, Fig. 1, and looking in the 165 direction of the arrows, and showing the de- 170 hydrating cones and gutter into which they discharge; Fig. 4 is a similar section on the 175 line 4—4, Fig. 1, looking in the direction 180 of the arrows; Fig. 5 is a detail view of a 185 suitable indicating device; Fig. 6 is a detail 190 plan view of the outlet from the grading vessel; Fig. 7 is an elevation thereof viewed 195 from the inside of the tank; Fig. 8 is a sec- 200 tional elevation on the line 8—8, Figs. 6 and 205 7; Fig. 9 is a plan view of the grading ves- 210 sel; and Fig. 10 is a detail sectional eleva- 215 tion of one of the dehydrating cones.

In the drawings, 1 indicates the table of 220 one form of glass grinding machine pro- 225 vided with a pair of runners 2 of the usual 230 form. These parts, however, are merely 235 typical of one form of grinding apparatus 240 to which the invention may be applied.

The table 1 is surrounded by a gutter 3 245 connecting with a cross gutter 4 which car- 250 ries the liquid and used abrasive from the 255 table over a screen 5 to the pit or sump 6 260 having the usual overflow 6^a for eliminating 265 the excess liquid, the slimes, and the abrad- 270 ing material too fine for further use, from 275 which it is drawn through pipe 7 by means 280 of a suitable pump, such as a centrifugal 285 pump 8 driven by a suitable motor 9, and is 290 forced through pipe 10 upwardly through 295 the bottom of the grading vessel 11, thereby 300 producing in said vessel an upward flow of 305 the liquid relative to the abrading material 310 and producing a separation of the material 315 into grades of different sizes, depending 320 upon the ratio of the weight of the particles 325 to the resistance to flow offered by the up- 330 ward current of liquid, as is well under- 335 stood and as described in my Patent No. 340 934,441, above identified. The pump 8 may 345 deliver the mixture of abrading material 350 and liquid to the grading vessel at a level 355 between its bottom and the upper level of 360 liquid therein, as described in my copending 365 application for method and apparatus for 370 applying abrasive material to grinding and 375 smoothing mechanism, filed August 9, 1915, 380 Serial No. 44622, in which case the grading 385 vessel will be provided with a supplemental 390 water supply connected thereto at a level 395 below that at which the abrading material 400 is introduced to said vessel for producing 405 or augmenting the upward flow of the 410 liquid relative to the downward movement 415 of the abrading material. The particular 420

425 arrangement shown is for use with a water 430 supply, the water being introduced through 435 a pipe 12 connected to a pump 13, the pump 440 being driven by a motor 14. The water 445 passes through a pipe 15 to a valve 16, the 450 valve being connected to a pipe 17 which 455 passes through a valve 18 to a pipe 19, the 460 pipe 19 being connected to a valve 20, the 465 valve 20 being connected to a pipe 21, the 470 pipe 21 being connected to a valve 22, the 475 valve 22 being connected to a pipe 23, the 480 pipe 23 being connected to a valve 24, the 485 valve 24 being connected to a pipe 25, the 490 pipe 25 being connected to a valve 26, the 495 valve 26 being connected to a pipe 27, the 500 pipe 27 being connected to a valve 28, the 505 valve 28 being connected to a pipe 29, the 510 pipe 29 being connected to a valve 30, the 515 valve 30 being connected to a pipe 31, the 520 pipe 31 being connected to a valve 32, the 525 valve 32 being connected to a pipe 33, the 530 pipe 33 being connected to a valve 34, the 535 valve 34 being connected to a pipe 35, the 540 pipe 35 being connected to a valve 36, the 545 valve 36 being connected to a pipe 37, the 550 pipe 37 being connected to a valve 38, the 555 valve 38 being connected to a pipe 39, the 560 pipe 39 being connected to a valve 40, the 565 valve 40 being connected to a pipe 41, the 570 pipe 41 being connected to a valve 42, the 575 valve 42 being connected to a pipe 43, the 580 pipe 43 being connected to a valve 44, the 585 valve 44 being connected to a pipe 45, the 590 pipe 45 being connected to a valve 46, the 595 valve 46 being connected to a pipe 47, the 600 pipe 47 being connected to a valve 48, the 605 valve 48 being connected to a pipe 49, the 610 pipe 49 being connected to a valve 50, the 615 valve 50 being connected to a pipe 51, the 620 pipe 51 being connected to a valve 52, the 625 valve 52 being connected to a pipe 53, the 630 pipe 53 being connected to a valve 54, the 635 valve 54 being connected to a pipe 55, the 640 pipe 55 being connected to a valve 56, the 645 valve 56 being connected to a pipe 57, the 650 pipe 57 being connected to a valve 58, the 655 valve 58 being connected to a pipe 59, the 660 pipe 59 being connected to a valve 60, the 665 valve 60 being connected to a pipe 61, the 670 pipe 61 being connected to a valve 62, the 675 valve 62 being connected to a pipe 63, the 680 pipe 63 being connected to a valve 64, the 685 valve 64 being connected to a pipe 65, the 690 pipe 65 being connected to a valve 66, the 695 valve 66 being connected to a pipe 67, the 700 pipe 67 being connected to a valve 68, the 705 valve 68 being connected to a pipe 69, the 710 pipe 69 being connected to a valve 70, the 715 valve 70 being connected to a pipe 71, the 720 pipe 71 being connected to a valve 72, the 725 valve 72 being connected to a pipe 73, the 730 pipe 73 being connected to a valve 74, the 735 valve 74 being connected to a pipe 75, the 740 pipe 75 being connected to a valve 76, the 745 valve 76 being connected to a pipe 77, the 750 pipe 77 being connected to a valve 78, the 755 valve 78 being connected to a pipe 79, the 760 pipe 79 being connected to a valve 80, the 765 valve 80 being connected to a pipe 81, the 770 pipe 81 being connected to a valve 82, the 775 valve 82 being connected to a pipe 83, the 780 pipe 83 being connected to a valve 84, the 785 valve 84 being connected to a pipe 85, the 790 pipe 85 being connected to a valve 86, the 795 valve 86 being connected to a pipe 87, the 800 pipe 87 being connected to a valve 88, the 805 valve 88 being connected to a pipe 89, the 810 pipe 89 being connected to a valve 90, the 815 valve 90 being connected to a pipe 91, the 820 pipe 91 being connected to a valve 92, the 825 valve 92 being connected to a pipe 93, the 830 pipe 93 being connected to a valve 94, the 835 valve 94 being connected to a pipe 95, the 840 pipe 95 being connected to a valve 96, the 845 valve 96 being connected to a pipe 97, the 850 pipe 97 being connected to a valve 98, the 855 valve 98 being connected to a pipe 99, the 860 pipe 99 being connected to a valve 100, the 865 valve 100 being connected to a pipe 101, the 870 pipe 101 being connected to a valve 102, the 875 valve 102 being connected to a pipe 103, the 880 pipe 103 being connected to a valve 104, the 885 valve 104 being connected to a pipe 105, the 890 pipe 105 being connected to a valve 106, the 895 valve 106 being connected to a pipe 107, the 900 pipe 107 being connected to a valve 108, the 905 valve 108 being connected to a pipe 109, the 910 pipe 109 being connected to a valve 110, the 915 valve 110 being connected to a pipe 111, the 920 pipe 111 being connected to a valve 112, the 925 valve 112 being connected to a pipe 113, the 930 pipe 113 being connected to a valve 114, the 935 valve 114 being connected to a pipe 115, the 940 pipe 115 being connected to a valve 116, the 945 valve 116 being connected to a pipe 117, the 950 pipe 117 being connected to a valve 118, the 955 valve 118 being connected to a pipe 119, the 960 pipe 119 being connected to a valve 120, the 965 valve 120 being connected to a pipe 121, the 970 pipe 121 being connected to a valve 122, the 975 valve 122 being connected to a pipe 123, the 980 pipe 123 being connected to a valve 124, the 985 valve 124 being connected to a pipe 125, the 990 pipe 125 being connected to a valve 126, the 995 valve 126 being connected to a pipe 127, the 1000 pipe 127 being connected to a valve 128, the 1005 valve 128 being connected to a pipe 129, the 1010 pipe 129 being connected to a valve 130, the 1015 valve 130 being connected to a pipe 131, the 1020 pipe 131 being connected to a valve 132, the 1025 valve 132 being connected to a pipe 133, the 1030 pipe 133 being connected to a valve 134, the 1035 valve 134 being connected to a pipe 135, the 1040 pipe 135 being connected to a valve 136, the 1045 valve 136 being connected to a pipe 137, the 1050 pipe 137 being connected to a valve 138, the 1055 valve 138 being connected to a pipe 139, the 1060 pipe 139 being connected to a valve 140, the 1065 valve 140 being connected to a pipe 141, the 1070 pipe 141 being connected to a valve 142, the 1075 valve 142 being connected to a pipe 143, the 1080 pipe 143 being connected to a valve 144, the 1085 valve 144 being connected to a pipe 145, the 1090 pipe 145 being connected to a valve 146, the 1095 valve 146 being connected to a pipe 147, the 1100 pipe 147 being connected to a valve 148, the 1105 valve 148 being connected to a pipe 149, the 1110 pipe 149 being connected to a valve 150, the 1115 valve 150 being connected to a pipe 151, the 1120 pipe 151 being connected to a valve 152, the 1125 valve 152 being connected to a pipe 153, the 1130 pipe 153 being connected to a valve 154, the 1135 valve 154 being connected to a pipe 155, the 1140 pipe 155 being connected to a valve 156, the 1145 valve 156 being connected to a pipe 157, the 1150 pipe 157 being connected to a valve 158, the 1155 valve 158 being connected to a pipe 159, the 1160 pipe 159 being connected to a valve 160, the 1165 valve 160 being connected to a pipe 161, the 1170 pipe 161 being connected to a valve 162, the 1175 valve 162 being connected to a pipe 163, the 1180 pipe 163 being connected to a valve 164, the 1185 valve 164 being connected to a pipe 165, the 1190 pipe 165 being connected to a valve 166, the 1195 valve 166 being connected to a pipe 167, the 1200 pipe 167 being connected to a valve 168, the 1205 valve 168 being connected to a pipe 169, the 1210 pipe 169 being connected to a valve 170, the 1215 valve 170 being connected to a pipe 171, the 1220 pipe 171 being connected to a valve 172, the 1225 valve 172 being connected to a pipe 173, the 1230 pipe 173 being connected to a valve 174, the 1235 valve 174 being connected to a pipe 175, the 1240 pipe 175 being connected to a valve 176, the 1245 valve 176 being connected to a pipe 177, the 1250 pipe 177 being connected to a valve 178, the 1255 valve 178 being connected to a pipe 179, the 1260 pipe 179 being connected to a valve 180, the 1265 valve 180 being connected to a pipe 181, the 1270 pipe 181 being connected to a valve 182, the 1275 valve 182 being connected to a pipe 183, the 1280 pipe 183 being connected to a valve 184, the 1285 valve 184 being connected to a pipe 185, the 1290 pipe 185 being connected to a valve 186, the 1295 valve 186 being connected to a pipe 187, the 1300 pipe 187 being connected to a valve 188, the 1305 valve 188 being connected to a pipe 189, the 1310 pipe 189 being connected to a valve 190, the 1315 valve 190 being connected to a pipe 191, the 1320 pipe 191 being connected to a valve 192, the 1325 valve 192 being connected to a pipe 193, the 1330 pipe 193 being connected to a valve 194, the 1335 valve 194 being connected to a pipe 195, the 1340 pipe 195 being connected to a valve 196, the 1345 valve 196 being connected to a pipe 197, the 1350 pipe 197 being connected to a valve 198, the 1355 valve 198 being connected to a pipe 199, the 1360 pipe 199 being connected to a valve 200, the 1365 valve 200 being connected to a pipe 201, the 1370 pipe 201 being connected to a valve 202, the 1375 valve 202 being connected to a pipe 203, the 1380 pipe 203 being connected to a valve 204, the 1385 valve 204 being connected to a pipe 205, the 1390 pipe 205 being connected to a valve 206, the 1395 valve 206 being connected to a pipe 207, the 1400 pipe 207 being connected to a valve 208, the 1405 valve 208 being connected to a pipe 209, the 1410 pipe 209 being connected to a valve 210, the 1415 valve 210 being connected to a pipe 211, the 1420 pipe 211 being connected to a valve 212, the 1425 valve 212 being connected to a pipe 213, the 1430 pipe 213 being connected to a valve 214, the 1435 valve 214 being connected to a pipe 215, the 1440 pipe 215 being connected to a valve 216, the 1445 valve 216 being connected to a pipe 217, the 1450 pipe 217 being connected to a valve 218, the 1455 valve 218 being connected to a pipe 219, the 1460 pipe 219 being connected to a valve 220, the 1465 valve 220 being connected to a pipe 221, the 1470 pipe 221 being connected to a valve 222, the 1475 valve 222 being connected to a pipe 223, the 1480 pipe 223 being connected to a valve 224, the 1485 valve 224 being connected to a pipe 225, the 1490 pipe 225 being connected to a valve 226, the 1495 valve 226 being connected to a pipe 227, the 1500 pipe 227 being connected to a valve 228, the 1505 valve 228 being connected to a pipe 229, the 1510 pipe 229 being connected to a valve 230, the 1515 valve 230 being connected to a pipe 231, the 1520 pipe 231 being connected to a valve 232, the 1525 valve 232 being connected to a pipe 233, the 1530 pipe 233 being connected to a valve 234, the 1535 valve 234 being connected to a pipe 235, the 1540 pipe 235 being connected to a valve 236, the 1545 valve 236 being connected to a pipe 237, the 1550 pipe 237 being connected to a valve 238, the 1555 valve 238 being connected to a pipe 239, the 1560 pipe 239 being connected to a valve 240, the 1565 valve 240 being connected to a pipe 241, the 1570 pipe 241 being connected to a valve 242, the 1575 valve 242 being connected to a pipe 243, the 1580 pipe 243 being connected to a valve 244, the 1585 valve 244 being connected to a pipe 245, the 1590 pipe 245 being connected to a valve 246, the 1595 valve 246 being connected to a pipe 247, the 1600 pipe 247 being connected to a valve 248, the 1605 valve 248 being connected to a pipe 249, the 1610 pipe 249 being connected to a valve 250, the 1615 valve 250 being connected to a pipe 251, the 1620 pipe 251 being connected to a valve 252, the 1625 valve 252 being connected to a pipe 253, the 1630 pipe 253 being connected to a valve 254, the 1635 valve 254 being connected to a pipe 255, the 1640 pipe 255 being connected to a valve 256, the 1645 valve 256 being connected to a pipe 257, the 1650 pipe 257 being connected to a valve 258, the 1655 valve 258 being connected to a pipe 259, the 1660 pipe 259 being connected to a valve 260, the 1665 valve 260 being connected to a pipe 261, the 1670 pipe 261 being connected to a valve 262, the 1675 valve 262 being connected to a pipe 263, the 1680 pipe 263 being connected to a valve 264, the 1685 valve 264 being connected to a pipe 265, the 1690 pipe 265 being connected to a valve 266, the 1695 valve 266 being connected to a pipe 267, the 1700 pipe 267 being connected to a valve 268, the 1705 valve 268 being connected to a pipe 269, the 1710 pipe 269 being connected to a valve 270, the 1715 valve 270 being connected to a pipe 271, the 1720 pipe 271 being connected to a valve 272, the 1725 valve 272 being connected to a pipe 273, the 1730 pipe 273 being connected to a valve 274, the 1735 valve 274 being connected to a pipe 275, the 1740 pipe 275 being connected to a valve 276, the 1745 valve 276 being connected to a pipe 277, the 1750 pipe 277 being connected to a valve 278, the 1755 valve 278 being connected to a pipe 279, the 1760 pipe 279 being connected to a valve 280, the 1765 valve 280 being connected to a pipe 281, the 1770 pipe 281 being connected to a valve 282, the 1775 valve 282 being connected to a pipe 283, the 1780 pipe 283 being connected to a valve 284, the 1785 valve 284 being connected to a pipe 285, the 1790 pipe 285 being connected to a valve 286, the 1795 valve 286 being connected to a pipe 287, the 1800 pipe 287 being connected to a valve 288, the 1805 valve 288 being connected to a pipe 289, the 1810 pipe 289 being connected to a valve 290, the 1815 valve 290 being connected to a pipe 291, the 1820 pipe 291 being connected to a valve 292, the 1825 valve 292 being connected to a pipe 293, the 1830 pipe 293 being connected to a valve 294, the 1835 valve 294 being connected to a pipe 295, the 1840 pipe 295 being connected to a valve 296, the 1845 valve 296 being connected to a pipe 297, the 1850 pipe 297 being connected to a valve 298, the 1855 valve 298 being connected to a pipe 299, the 1860 pipe 299 being connected to a valve 300, the 1865 valve 300 being connected to a pipe 301, the 1870 pipe 301 being connected to a valve 302, the 1875 valve 302 being connected to a pipe 303, the 1880 pipe 303 being connected to a valve 304, the 1885 valve 304 being connected to a pipe 305, the 1890 pipe 305 being connected to a valve 306, the 1895 valve 306 being connected to a pipe 307, the 1900 pipe 307 being connected to a valve 308, the 1905 valve 308 being connected to a pipe 309, the 1910 pipe 309 being connected to a valve 310, the 1915 valve 310 being connected to a pipe 311, the 1920 pipe 311 being connected to a valve 312, the 1925 valve 312 being connected to a pipe 313, the 1930 pipe 313 being connected to a valve 314, the 1935 valve 314 being connected to a pipe 315, the 1940 pipe 315 being connected to a valve 316, the 1945 valve 316 being connected to a pipe 317, the 1950 pipe 317 being connected to a valve 318, the 1955 valve 318 being connected to a pipe 319, the 1960 pipe 319 being connected to a valve 320, the 1965 valve 320 being connected to a pipe 321, the 1970 pipe 321 being connected to a valve 322, the 1975 valve 322 being connected to a pipe 323, the 1980 pipe 323 being connected to a valve 324, the 1985 valve 324 being connected to a pipe 325, the 1990 pipe 325 being connected to a valve 326, the 1995 valve 326 being connected to a pipe 327, the 2000 pipe 327 being connected to a valve 328, the 2005 valve 328 being connected to a pipe 329, the 2010 pipe 329 being connected to a valve 330, the 2015 valve 330 being connected to a pipe 331, the 2020 pipe 331 being connected to a valve 332, the 2025 valve 332 being connected to a pipe 333, the 2030 pipe 333 being connected to a valve 334, the 2035 valve 334 being connected to a pipe 335, the 2040 pipe 335 being connected to a valve 336, the 2045 valve 336 being connected to a pipe 337, the 2050 pipe 337 being connected to a valve 338, the 2055 valve 338 being connected to a pipe 339, the 2060 pipe 339 being connected to a valve 340, the 2065 valve 340 being connected to a pipe 341, the 2070 pipe 341 being connected to a valve 342, the 2075 valve 342 being connected to a pipe 343, the 2080 pipe 343 being connected to a valve 344, the 2085 valve 344 being connected to a pipe 345, the 2090 pipe 345 being connected to a valve 346, the 2095 valve 346 being connected to a pipe 347, the 2100 pipe 347 being connected to a valve 348, the 2105 valve 348 being connected to a pipe 349, the 2110 pipe 349 being connected to a valve 350, the 2115 valve 350 being connected to a pipe 351, the 2120 pipe 351 being connected to a valve 352, the 2125 valve 352 being connected to a pipe 353, the 2130 pipe 353 being connected to a valve 354, the 2135 valve 354 being connected to a pipe 355, the 2140 pipe 355 being connected to a valve 356, the 2145 valve 356 being connected to a pipe 357, the 2150 pipe 357 being connected to a valve 358, the 2155 valve 358 being connected to a pipe 359, the 2160 pipe 359 being connected to a valve 360, the 2165 valve 360 being connected to a pipe 361, the 2170 pipe 361 being connected to a valve 362, the 2175 valve 362 being connected to a pipe 363, the 2180 pipe 363 being connected to a valve 364, the 2185 valve 364 being connected to a pipe 365, the 2190 pipe 365 being connected to a valve 366, the 2195 valve 366 being connected to a pipe 367, the 2200 pipe 367 being connected to a valve 368, the 2205 valve 368 being connected to a pipe 369, the 2210 pipe 369 being connected to a valve 370, the 2215 valve 370 being connected to a pipe 371, the 2220 pipe 371 being connected to a valve 372, the 2225 valve 372 being connected to a pipe 373, the 2230 pipe 373 being connected to a valve 374, the 2235 valve 374 being connected to a pipe 375, the 2240 pipe 375 being connected to a valve 376, the 2245 valve 376 being connected to a pipe 377, the 2250 pipe 377 being connected to a valve 378, the 2255 valve 378 being connected to a pipe 379, the 2260 pipe 379 being connected to a valve 380, the 2265 valve 380 being connected to a pipe 381, the 2270 pipe 381 being connected to a valve 382, the 2275 valve 382 being connected to a pipe 383, the 2280 pipe 383 being connected to a valve 384, the 2285 valve 384 being connected to a pipe 385, the 2290 pipe 385 being connected to a valve 386, the 2295 valve 386 being connected to a pipe 387, the 2300 pipe 387 being connected to a valve 388, the 2305 valve 388 being connected to a pipe 389, the 2310 pipe 389 being connected to a valve 390, the 2315 valve 390 being connected to a pipe 391, the 2320 pipe 391 being connected to a valve 392, the 2325 valve 392 being connected to a pipe 393, the 2330 pipe 393 being connected to a valve 394, the 2335 valve 394 being connected to a pipe 395, the 2340 pipe 395 being connected to a valve 396, the 2345 valve 396 being connected to a pipe 397, the 2350 pipe 397 being connected to a valve 398, the 2355 valve 398 being connected to a pipe 399, the 2360 pipe 399 being connected to a valve 400, the 2365 valve 400 being connected to a pipe 401, the 2370 pipe 401 being connected to a valve 402, the 2375 valve 402 being connected to a pipe 403, the 2380 pipe 403 being connected to a valve 404, the 2385 valve 404 being connected to a pipe 405, the 2390 pipe 405 being connected to a valve 406, the 2395 valve 406 being connected to a pipe 407, the 2400 pipe 407 being connected to a valve 408, the 2405 valve 408 being connected to a pipe 409, the 2410 pipe 409 being connected to a valve 410, the 2415 valve 410 being connected to a pipe 411, the 2420 pipe 411 being connected to a valve 412, the 2425 valve 412 being connected to a pipe 413, the 2430 pipe 413 being connected to a valve 414, the 2435 valve 414 being connected to a pipe 415, the 2440 pipe 415 being connected to a valve 416, the 2445 valve 416 being connected to a pipe 417, the 2450 pipe 417 being connected to a valve 418, the 2455 valve 418 being connected to a pipe 419, the 2460 pipe 419 being connected to a valve 420, the 2465 valve 420 being connected to a pipe 421, the 2470 pipe 421 being connected to a valve 422, the 2475 valve 422 being connected to a pipe 423, the 2480 pipe 423 being connected to a valve 424, the 2485 valve 424 being connected to a pipe 425, the 2490 pipe 425 being connected to a valve 426, the 2495 valve 426 being connected to a pipe 427, the 2500 pipe 427 being connected to a valve 428, the 2505 valve 428 being connected to a pipe 429, the 2510 pipe 429 being connected to a valve 430, the 2515 valve 430 being connected to a pipe 431, the 2520 pipe 431 being connected to a valve 432, the 2525 valve 432 being connected to a pipe 433, the 2530 pipe 433 being connected to a valve 434, the 2535 valve 434 being connected to a pipe 435, the 2540 pipe 435 being connected to a valve 436, the 2545 valve 436 being connected to a pipe 437, the 2550 pipe 437 being connected to a valve 438, the 2555 valve 438 being connected to a pipe 439, the 2560 pipe 439 being connected to a valve 440, the 2565 valve 440 being connected to a pipe 441, the 2570 pipe 441 being connected to a valve 442, the 2575 valve 442 being connected to a pipe 443, the 2580 pipe 443 being connected to a valve 444, the 2585 valve 444 being connected to a pipe 445, the 2590 pipe 445 being connected to a valve 446, the 2595 valve 446 being connected to a pipe 447, the 2600 pipe 447 being connected to a valve 448, the 2605 valve 448 being connected to a pipe 449, the 2610 pipe 449 being connected to a valve 450, the 2615 valve 450 being connected to a pipe 451, the 2620 pipe 451 being connected to a valve 452, the 2625 valve 452 being connected to a pipe 453, the 2630 pipe 453 being connected to a valve 454, the 2635 valve 454 being connected to a pipe 455, the 2640 pipe 455 being connected to a valve 456, the 2645 valve 456 being connected to a pipe 457, the 2650 pipe 457 being connected to a valve 458, the 2655 valve 458 being connected to a pipe 459, the 2660 pipe 459 being connected to a valve 460, the 2665 valve 460 being connected to a pipe 461, the 2670 pipe 461 being connected to a valve 462, the 2675 valve 462 being connected to a pipe 463, the 2680 pipe 463 being connected to a valve 464, the 2685 valve 464 being connected to a pipe 465, the 2690 pipe 465 being connected to a valve 466, the 2695 valve 466 being connected to a pipe 467, the 2700 pipe 467 being connected to a valve 468, the 2705 valve 468 being connected to a pipe 469, the 2710 pipe 469 being connected to a valve 470, the 2715 valve 470 being connected to a pipe 471, the 2720 pipe 471 being connected to a valve 472, the 2725 valve 472 being connected to a pipe 473, the 2730 pipe 473 being connected to a valve 474, the 2735 valve 474 being connected to a pipe 475, the 2740 pipe 475 being connected to a valve 476, the 2745 valve 476 being connected to a pipe 477, the 2750 pipe 477 being connected to a valve 478, the 2755 valve 478 being connected to a pipe 479, the 2760 pipe 479 being connected to a valve 480, the 2765 valve 480 being connected to a pipe 481, the 2770 pipe 481 being connected to a valve

manner in which the abrading material is delivered to the grading vessel, however, is immaterial and forms no part of the present invention and consequently need not be further described.

The grading vessel 11 is designed to grade the new material and regrade all of the used material and to continuously maintain in said vessel (in well defined strata or zones) all of the different grades of material above a size too fine for further use. The material too fine for further use, including the dirt and scum, escapes constantly through an overflow pipe 12 which discharges into the gutter 3 at the point marked 22, so that the water carrying said material is used for washing out the ditches and returning the abrading material discharged from the table to the sump or pit, 20 the useless material to be eliminated through overflow 6* and the useful material to be reintroduced to the grading vessel.

The fresh abrading material, such as coarse sand, may be added to the system at any point, either into the grading vessel 11 or upon the table 1, but preferably is supplied to the sump 6 from a suitable bin or hopper 15 fed by a clam shell bucket 14 and having a valved outlet 16 arranged to deliver the sand into a measuring box 17, large enough to hold sufficient sand for one complete grinding operation. The sand is washed from the outlet 18 of the measuring box by a water supply through a pipe 19, 35 being discharged through the screen 5 into the sump 6.

The grading vessel 11 may be of any suitable size or form, but preferably has its lower portion in the form of a cone pointing downwardly, and having an upper portion 20 of cylindrical form, the walls of the vessel having such slopes that the velocity of the upwardly flowing liquid therein will decrease at such a rate that the particles of abrasive material assume positions at different levels therein according to their size, weight or other characteristics, as is now well understood. The upper portion of the vessel is made cylindrical in order to enable 50 the use of a smaller vessel and also secure a denser mixture of the finer grades with a smaller total quantity of the fine material in the grading vessel and to also serve as a reservoir for the finer grades superposed 55 upon the lower portion of the grading vessel, thereby dispensing with a separate vessel for receiving, collecting and condensing the finer grades.

The finer grades collected in the upper 60 portion of the grading vessel are condensed, or thickened by eliminating the surplus liquid from the various levels in the upper portion of the grading vessel, but without withdrawing any of the useful fine material therefrom, so as to secure the desired

density and distribution of the mixture. In the apparatus shown the cylindrical upper portion 20 of the grading vessel is provided with an annular gutter or trough 21, suitably supported within the wall of said vessel, to receive over its inner wall an overflow of the liquid in the grading vessel. The bottom of the gutter is inclined downwardly in opposite directions circumferentially of the grading vessel from one side 75 to the other, and at its lowest point said gutter communicates through an opening in its side wall and through the side wall of the tank with the overflow pipe 12 heretofore referred to. Within the cylindrical 80 portion of the grading vessel and at different levels therein are located a series of small hollow dehydrating cones 22, with their smaller ends up, communicating with upwardly extending pipes 23 discharging 85 into the gutter 21, said pipes being provided with suitable regulating valves 24.

When the valves 24 are fully closed no liquid or abrading material can flow upwardly into or through the cones 22, but if 90 said valves are opened the liquid flows out through the cones 22 and pipes 23 into the gutter 21, the velocity of flow increasing with the size of the opening through said valves. When liquid is flowing upwardly 95 through the cones 22 and pipes 23 the velocity of flow increases from the bottom of the cone upwardly and reaches a maximum at the pipe 23. Each valve 24 is adjusted so that the velocity of flow in its cone at a 100 level between its top and bottom, say at the level A, Fig. 10, is equal to the velocity of flow of the mixture in the grading vessel at the level B at the bottom of the cone. The velocity of the liquid between levels A 105 and B is therefore something less than at said levels, and is insufficient to lift into the cone 22 any abrading material lying in equilibrium at the level B. Consequently each cone abstracts or removes from the 110 grading vessel at its particular level some of the liquid in the mixture, but without removing any abrading material normally belonging in that zone.

The discharge of liquid at each of the 115 cones 22 progressively reduces the upward velocity in the cylindrical portion 21 in the grading vessel by a series of steps so that the finer particles are separated into grades distributed at various levels in the grading vessel. At each level a certain grade or size of material, between definite limits gradually accumulates, said grade becoming more and more dense as the dehydrating 120 operations proceed. The grades become 125 finer and finer upward between the different levels in the vessel as the interstitial velocity of the liquid decreases. The several zones between the bottoms of the cones 22 therefore form a series of traps, each 130

accumulating its own particular grade of fine material and condensing it by abstracting the superfluous liquid therefrom, so that these finer grades are collected and stored during the several cycles of the rough grinding operation for later use during finishing. The character and position of these grades can be regulated by means of the valves 24.

10 Provision is made for separately withdrawing the several grades from the grading vessel by providing a plurality of withdrawal pipes, the number thereof depending upon the number of grades which are 15 to be separately withdrawn. Three such pipes are shown in the drawings and are marked respectively 26, 27 and 28, and all pass out through the walls of the grading vessel at the same level, thereby contributing 20 to the maintenance of a constant head or pressure in the supply of mixture to the table. As shown, these pipes are all connected to a common casting or conducting member 29 which is secured to the wall of 25 the grading vessel and is provided with a plurality of inwardly projecting tubular portions, one for the attachment of each of the withdrawal pipes. As shown, the withdrawal pipe 26 has its inner end opening 30 near the bottom of the grading vessel 11, in the coarse sand zone; the intermediate withdrawal pipe 27 has its inner end opening at a point between the top and bottom of the cone, in the intermediate sand grade 35 zone, while the withdrawal pipe 28 is in the form of a flexible hose or pipe of sufficient length to reach to the bottom and also to the top of the grading vessel and having its free end vertically movable, as herein-after described, so that it can take the sand 40 out of said grading vessel at any desired point.

The several withdrawal pipes are constantly open so that water and abrasive material from each of the several grades in 45 which said pipes terminate is constantly discharged, thereby further contributing to the maintenance of a uniform pressure and uniform head in the grading vessel. As 50 shown, the openings through the casting 29 discharge into a vessel or casing 30 secured to the outer wall of the grading vessel and provided with an outlet conduit 31 leading to the sump 6. Pivotally mounted adjacent 55 to each discharge opening through the casting 29 is a discharge pipe, which pipes are marked respectively 26^a, 27^a and 28^a, and are so mounted and have their inner ends so formed that when lowered they fit over 60 the respective discharge openings in the casting 29 and form a conduit for conducting the discharge through that particular opening to a trough 32 extending through the outer wall of the vessel or casing 30 and 65 leading to the spout 33 which projects over

the grinding table 1, preferably between the runners 2, and which is perforated to discharge the mixture of sand and water onto the table. The discharge pipes 26^a, 27^a and 28^a are preferably bent to substantially 70 goose-neck form, as shown, although this is not essential; and are arranged to be swung upwardly about their pivots by suitable operating cords 26^b, 27^b and 28^b, each of which is knotted so that it may be slipped into a 75 notch in a holding member 34, or provided with other means whereby the pipe can be held in elevated position.

When all of the pipes are elevated the mixture discharging through each of the 80 withdrawal pipes 26, 27 and 28 returns through conduit 31 to the sump 6, but whenever one of said pipes is lowered, the mixture coming through the corresponding discharge pipe is conducted to the table. By 85 this arrangement, therefore, the desired grade can be conducted to the table by merely lowering the proper discharge pipe 26^a, 27^a or 28^a, and that particular grade will 90 continue to be supplied to the table as long as that discharge pipe remains in its lowered position.

In order to bring the inner open end of withdrawal pipe 28 to different heights for withdrawing successively finer grades, as is 95 necessary during the finishing operation, its free end is supplied with a weight 39 for sinking the pipe. This weight is connected by a cord or cable 40, which passes over a sheave or pulley 41, to a float 42 in a cylinder 43 supported at the side of the grading vessel 11. Connected to the lower end of cylinder 43 is a water pipe 44 which preferably extends to a point adjacent to the front of the table where it is provided with 100 a suitable three-way cock or valve 45 which has a discharge outlet and also communicates with a water supply, so that by merely setting said cock to the proper position water may be admitted to the cylinder 43 to 110 lift the float 42 and allow the weight 39 to sink the end of the flexible hose 28, or may be discharged from cylinder 43 and thus allow the float 42 to sink and elevate the end of flexible pipe 28 in the grading vessel. 115

Preferably, a second cable or cord 46 is connected to the float 42 and passes over pulley 41 and over a second pulley 47 to the opposite side of the tank where it operates a suitable indicating means, shown as a 120 weight 38 which is preferably held at the same level as the weight 39, so that the position of weight 38 indicates the exact position of the free open end of pipe 28 in the grading vessel.

Preferably, also, suitable means is provided for indicating to the operator the condition of the mixture within the grading vessel. The indicating means shown comprises a suitable displacement member or 125

hydrometer 54 which is so constructed and so loaded as to assume a state of equilibrium at a level between the coarse and intermediate grades of abrasive material, although it may lie at any desired level. This hydrometer is connected by a cord 55, lever 56 pivoted at 57 and counterweighted at 58, and cord 59, to a suitable indicator, shown as an electric lamp 60 arranged to move up and down in casing 61 having a plurality of windows 62 located at different levels and preferably covered with different colored glasses, such as red for the upper window, white for the intermediate and green for the bottom window.

The position of the hydrometer 54 depends upon the density of the mixture in which it is immersed. It is entirely immersed in the liquid and rises as the amount of abrasive material in suspension increases, and falls as the amount of abrasive material decreases. It is of such a size vertically of the grader that it is affected by changes in density in practically only a single grade or zone of material, which may be, say, the coarse sand, in which case the indicator 60 gives a visual indication of the condition of the coarse sand mixture, that is, its density and, roughly, the amount of material therein, while variations in the density of the other grades do not affect the hydrometer. This indicator also advises the grinding foreman of the condition of each table in a series of tables, that is, whether a table is just beginning the rough or facing operation, whether it is at the intermediate grinding operation, or whether it is doing fine grinding or finishing. By watching the changes in the indicators on each of a series of grinding tables the foreman can tell at a glance whether the tables are properly supplied with sand as well as the character of the operation then in progress, and can so adjust the amount of coarse sand used at each facing operation that the proper mixture will be insured.

In carrying out the method on the apparatus described the sump 6 and grading vessel 11 are first filled with water and the pump 8 is started to circulate the water. All of the discharge pipes 26^a, 27^a and 28^a are elevated so that the liquid is discharged into the casing or vessel 30 and returns through the pipe 31 to the sump 6. The pump runs continuously and at such a speed that the velocity of flow upwardly in the grading vessel is maintained uniform and also at a speed sufficient to produce an overflow through the several dehydrating cones 17 and the overflow pipe 12.

A measured charge of sand sufficient for a complete single grinding operation from roughing to finishing is measured into the hopper 17 and delivered or washed into the sump at such a rate as to secure the proper

density of the mixture and so that all of the sand gets into the circulation system before the fine grinding begins. This sand is carried up into the grading vessel and is graded according to its size, the larger particles assuming positions near the bottom of the cone and the grades becoming finer and finer up through the conical and cylindrical portions of the vessel. All dirt, scum and material too fine for use flows over into the gutter 21, together with the clear liquid eliminated at the various levels by the dehydrating cones, and delivered through the outlet 12 to the gutter 3 and returns to the sump where the excess water and slimes are eliminated from the system through overflow 6^a. Since the coarse sand at first predominates, the mixture in the bottom of the cone 11 is dense so that the hydrometer 54 rises and moves the indicating lamp 60 to a position opposite the lower window in casing 61 and displaying a green light, which means that the system is supplied with the proper quantity of coarse sand for economically effecting the rough grinding.

By properly manipulating the several discharge pipes 26^a, 27^a and 28^a, the several grades may be supplied from the grading vessel to the grinding table separately and independently and in any order and to any extent or degree desired. During the rough grinding, pipe 26^a is lowered to supply coarse material from near the bottom of the grading vessel into the trough 52 from which it flows to the spout 53 and is discharged upon the table, while the discharge pipes 27^a and 28^a are in elevated position so that the mixture discharging through withdrawal pipes 27 and 28 returns to the sump 6. When the whole batch of sand has been introduced into the sump and carried to the grader the hydrometer is in its highest position, and as the grinding proceeds and the coarse sand is reduced in size it gradually falls as the sand supplied to the table from the pipe 26^a becomes finer and finer. When the rough grinding operation has proceeded far enough the discharge pipe 26^a is lifted and the discharge pipe 27^a is lowered, and thereafter a considerably finer grade of material is delivered to the table from a level between the top and bottom of the cone, while for the final finishing operation the pipe 27^a is lifted and the pipe 28^a is lowered, thereby discharging into the trough 52 material coming through the withdrawal pipe 28.

During the rough grinding some of the sand is thrown off the table in the condition in which it is received, especially during the stage of adjusting the runners into full contact and full pressure with the table. The material so thrown off the table into the gutter 3 returns to the sump and back again into the grading vessel. During all of the

grinding operations some of the sand is broken up by the grinding action, producing grades of smaller size, some mud and some material too fine for further use. During each cycle of the circulation the mud and material too fine for further use are carried off through the overflow pipe 12, while all material still of a size capable of further use is returned to the grading vessel and regraded and is condensed or thickened by the dehydrating cones.

The final finishing is done with the several grades of abrasive material collected and trapped in suspension in the cylindrical portion 20 of the grading vessel. The inner open end of pipe 28 is placed in the zone of the grade with which the finishing operation is to begin, say, at the bottom on the cylindrical portion 20 of the vessel 11, and may then be raised at intervals by a series of steps or jumps so as to deliver to the grinding table successively portions of the material of finer and finer grades, until the smoothing operation is completed. Preferably, however, the open end of pipe 28 is moved upward at a uniform rate of speed, traversing in turn each of the various levels in the cylinder 20 in a series of imperceptible changes, so that the grade of material supplied to the table changes gradually from the intermediate grade near the top of the cone to the very finest grade at the top of the cylinder. To secure uniform results and also to regulate the time of grinding, the three-way cock 45 is so set as to discharge the water from the cylinder 43 at just such a rate that the float 42 will raise the open end of pipe 28 at the proper rate of speed. If desired, the outlet of cock 45 may be made of such a size as to constitute the limit of the maximum rate of discharge. This does away with the necessity of watching the apparatus closely during the fine grinding and adjusting the flexible pipe at proper intervals for changes in grades.

During all of the grinding operation, from roughing to finishing, the abrasive material is in suspension in a liquid and is circulated repeatedly from the grading vessel to the grinding table, then to the sump, and back to the grading vessel; slimes and fine material being separated at the sump during the course of each cycle. After the introduction of the initial supply or charge of abrading material from the hopper 17 no more abrading is introduced into the system, but the original charge becomes finer and finer during the progress of the grinding operation, and is collected and condensed in the upper portion of the grader to supply the necessary amount of fine sand for the finishing.

As the grinding operation proceeds the density of the coarse mixture in the grading vessel decreases and the hydrometer 55

sinks, thereby raising the lamp 60 and changing the indication from green to white and then to red, thereby indicating to the foreman the particular stage of grinding operation.

When the grinding operation is completed all of the discharge pipes 26^a, 27^a and 28^a are raised and the mixture is allowed to flow from the grading tank into the vessel or casing 30 from which it flows to the sump 75 6, thereby enabling the circulation to be continued between successive grinding operations, or during the time that the glass on the table is being changed.

Usually, upon starting a given system a slight excess of coarse sand is supplied with each of the first few batches, so as to insure sufficient coarse sand for the rough grinding, and which excess is broken up on the table to form finer grades which accumulate in the cylindrical portion 20 of the grading vessel and form a reserve supply of fine material which can be drawn upon in case it is necessary or desired to finish or refinish a side of glass without first going through the grinding operation. After a sufficient excess of fine sand has accumulated in the vessel 11 the measured batches of sand thereafter introduced are calculated so as to be just sufficient for one complete grinding operation. The mud and fine material washed out through the overflow during each grinding operation are equal in quantity to the new batch of sand supplied to the system for each grinding operation. By operating the system in this manner each batch of sand introduced into the system is graded and supplied to the table under conditions identical with those in the preceding operation, and these conditions are maintained during the entire course of each and every grinding operation. The method of grading abrading material in a vessel, conducting the material from the grading vessel to the grinding mechanism, and varying the grade of material conducted to the grinding mechanism by imperceptible changes, is not claimed herein but is claimed in my application Serial No. 806,594, filed December 13, 1913.

What I claim is:

1. The method described, consisting in separating abrading material mixed with a liquid in a vessel into different grades, eliminating surplus liquid from various levels in said vessel, and withdrawing said grades and conducting the same to grinding mechanism.

2. The method described, consisting in separating abrading material mixed with a liquid in a vessel into different grades, condensing several grades in said vessel, and withdrawing said grades and conducting the same to grinding mechanism.

3. The method described, consisting in

- separating abrading material mixed with a liquid in a vessel into different grades, conducting said grades from said vessel to grinding mechanism and returning the same to and introducing the same into said vessel, and simultaneously condensing the finer grades in said vessel. 5
4. The method described, consisting in separating abrading material mixed with a liquid in a vessel into different grades, withdrawing the coarser grades and conducting the same to grinding mechanism, returning the same to and introducing the same into the grading vessel, and simultaneously collecting and condensing the finer grades in said vessel for use during finishing. 10
5. The method described, consisting in separating abrading material mixed with a liquid in a vessel into different grades, withdrawing the coarser grades and conducting the same to grinding mechanism, returning the same to and introducing the same into the grading vessel, and simultaneously eliminating surplus liquid from various levels in said vessel to condense the grades therein. 20
6. The method described, consisting in separating abrading material mixed with a liquid in a vessel into different grades, circulating the coarser grades between the grading vessel and grinding mechanism during the facing operation, and simultaneously collecting, regrading and condensing the finer grades in said grading vessel, said grading, regrading and circulation being carried on in an uninterrupted cycle with the material constantly mixed with a liquid. 30
7. The method described, consisting in separating abrading material mixed with a liquid in a vessel into different grades, withdrawing the coarser grades and circulating the same from the grading vessel to and from the grinding apparatus during the rough grinding operation, eliminating the surplus liquid from various levels in said vessel and thereby condensing the several grades therein, and withdrawing the finer grades from said vessel and conducting the same to the grinding apparatus for the finishing operation. 40
8. The method of grinding and smoothing glass, which consists in placing the rough glass in a grinding machine, feeding new coarse sand and water to said machine in sufficient quantity to effect the rough grinding, circulating the sand and water between the grinding machine and a grading vessel, in the course of each cycle regrading the material in suspension in a liquid in said vessel and collecting the fine material therein for use during finishing, and simultaneously eliminating water from various levels in said vessel to condense the grades 65 therein. 50
9. The method described, consisting in separating abrading material mixed with a liquid in a vessel into different grades, eliminating surplus liquid from various levels in said vessel to condense the grades therein, withdrawing said grades and conducting the same to grinding mechanism, and producing a visible indication of the density of the mixture in said vessel. 75
10. Apparatus of the character described, comprising in combination, grinding mechanism, a grading vessel, means for producing in said vessel an upward flow or travel of the liquid relative to the material to separate the material into grades, means for conducting different grades independently from said vessel to the grinding mechanism, and means for eliminating surplus liquid from various levels in said vessel. 80
11. Apparatus of the character described, comprising in combination, grinding mechanism, a grading vessel, means for producing in said vessel an upward flow or travel of the liquid relative to the material to separate the material into grades, means for conducting different grades independently from said vessel to the grinding mechanism, and means for simultaneously condensing the several grades in said vessel. 85
12. Apparatus of the character described, comprising in combination, grinding mechanism, a grading vessel, means for producing in said vessel an upward flow or travel of the liquid relative to the material to separate the material into grades, means for conducting different grades independently from said vessel to the grinding mechanism, and means for simultaneously collecting the finer grades in said vessel and eliminating surplus liquid from various levels in said vessel to condense the finer grades therein. 95
13. Apparatus of the character described, comprising in combination, grinding mechanism, a grading vessel, means for producing in said vessel an upward flow or travel of the material relative to the liquid to separate the material into grades, means for circulating several grades of material in suspension in a liquid between said vessel and grinding mechanism, and means for simultaneously condensing the finer grades of abrading material in said vessel. 100
14. Apparatus of the character described, comprising in combination, grinding mechanism, a grading vessel, means for producing in said vessel an upward flow or travel of the material relative to the liquid to separate the material into grades, means for circulating several grades of material in suspension in a liquid between said vessel and grinding mechanism, and means for simultaneously eliminating water from various levels in said vessel to condense the grades 115 therein. 120
15. Apparatus of the character described, comprising in combination, grinding mechanism, a grading vessel, means for producing in said vessel an upward flow or travel of the material relative to the liquid to separate the material into grades, means for circulating several grades of material in suspension in a liquid between said vessel and grinding mechanism, and means for simultaneously condensing the finer grades 125 of abrading material in said vessel. 125

ously withdrawing surplus liquid from various levels in said vessel while retaining the abrading material at said levels to thereby condense the mixture in said vessel.

5 15. Apparatus of the character described, comprising in combination, grinding mechanism, a grading vessel, means for producing in said vessel an upward flow or travel of the liquid relative to the material to separate the material into grades, means for conducting different grades independently from said vessel to the grinding mechanism, and a plurality of outlets at different levels in the upper portion of said vessel 10 for withdrawing liquid from said levels to condense the various grades in the upper portion of said vessel.

16. Apparatus of the character described, comprising in combination, grinding mechanism, a grading vessel, means for producing in said vessel an upward flow or travel of the liquid relative to the material to separate the material into grades, means for conducting said grades independently from 20 said vessel to the grinding mechanism, and a plurality of cones having their open lower ends located at different levels in said vessel for withdrawing superfluous liquid from said levels while retaining and condensing 25 the various grades in said vessel.

17. Apparatus of the character described, comprising in combination, grinding mechanism, a grading vessel, means for producing in said vessel an upward flow or travel of the liquid relative to the material to separate the material into grades, means for conducting different grades independently from 35 said vessel to the grinding mechanism, means for returning said material in suspension in a liquid from the grinding mechanism to said vessel and introducing the same thereto, and a plurality of cones at different levels in said vessel for withdrawing superfluous liquid from said levels 40 while retaining and condensing the various grades in said vessel.

18. The herein described method which consists in grading abrading material in a vessel while in suspension in a liquid to 50 cause the grades to assume different levels, withdrawing some of the grades while in suspension in the liquid from said grading vessel and conducting the same to grinding mechanism while leaving other grades in 55 said vessel, and varying the grades so conducted to the grinding mechanism by imperceptible changes.

19. The herein described method which consists in grading abrading material in a 60 vessel while in suspension in a liquid to cause the grades to assume different levels, withdrawing said material while in suspension in the liquid from said vessel and conducting the same to grinding mechanism, 65 returning the same while still mixed with

the liquid to and introducing the same into said grading vessel and re-grading the same, said grading, grinding, re-grading and circulation being carried on in an uninterrupted cycle with the material constantly mixed 70 with the liquid, and varying some of the grades conducted to the grinding mechanism progressively and by imperceptible changes.

20. Apparatus of the character described 75 comprising, in combination, grinding mechanism, a grading vessel, means for grading abrading material in said vessel while in suspension in a liquid to cause the grades to assume different levels, and means for conducting the material in suspension in the 80 liquid from the grading vessel to the grinding mechanism arranged to automatically and uniformly vary the grade of material conducted to said mechanism.

21. Apparatus of the character described 85 comprising, in combination, grinding mechanism, a grading vessel, means for grading abrading material in said vessel while in suspension in a liquid to cause the grades to assume different levels, a flexible pipe lying 90 within the grading vessel for withdrawing the mixture from said vessel, and automatic means for progressively moving the open end of said pipe upward through the mixture in said vessel to thereby progressively 95 vary the grade of material conducted to the grinding mechanism.

22. Apparatus of the character described comprising, in combination, grinding mechanism, a grading vessel, means for grading 100 abrading material in said vessel while in suspension in a liquid to cause the grades to assume different levels, a flexible pipe lying within the grading vessel for withdrawing the mixture from said vessel, automatic means for progressively moving the open end of said pipe upward through the mixture in said vessel to thereby progressively 105 vary the grade of material conducted to the grinding mechanism, and means for 110 indicating the position of the open end of said pipe in the grading vessel.

23. Apparatus of the character described comprising, in combination, grinding mechanism, a grading vessel, means for grading 115 abrading material in said vessel while in suspension in a liquid to cause the grades to assume different levels, a flexible pipe lying within the grading vessel for withdrawing the mixture from said vessel, a reservoir for 120 liquid, a float in said reservoir, connections between said float and the open end of said flexible pipe for elevating the latter, and means for withdrawing liquid from said reservoir to elevate the inner open end of 125 said pipe.

24. Apparatus of the character described comprising, in combination, grinding mechanism, a grading vessel, means for grading 130 abrading material in said vessel while in

suspension in a liquid to cause the grades to assume different levels, a flexible pipe lying within the grading vessel for withdrawing the mixture from said vessel, a reservoir for liquid, a float in said reservoir, connections between said float and the open end of said flexible pipe for elevating the latter, means for withdrawing liquid from said reservoir to elevate the inner open end of said pipe, 10 and an indicator vertically movable with said pipe to indicate the level of the latter in said vessel.

25. Apparatus of the character described comprising, in combination, grinding mechanism, a grading vessel, means for grading abrading material in said vessel while in suspension in a liquid to cause the grades to assume different levels, a flexible pipe lying within the grading vessel for withdrawing the mixture from said vessel, a reservoir for liquid, a float in said reservoir, variable means for withdrawing liquid from said reservoir, and connections between said float and the open end of said flexible pipe for 20 elevating the latter.

26. Apparatus of the character described comprising, in combination, grinding mechanism, a grading vessel, means for grading abrading material in said vessel while in 30 suspension in a liquid to cause the grades to assume different levels, a flexible pipe lying

within the grading vessel for withdrawing the mixture from said vessel, a reservoir for liquid, a float in said reservoir, variable means for withdrawing liquid from said 35 reservoir, connections between said float and the open end of said flexible pipe for elevating the latter, and an indicator vertically movable on the outside of the grading vessel and arranged to rise and fall in unison with 40 said pipe to thereby indicate its position in the grading vessel.

27. Apparatus of the character described comprising, in combination, grinding mechanism, a grading vessel, means for grading 45 abrading material in said vessel while in suspension in a liquid to cause the grades to assume different levels, a flexible pipe lying within the grading vessel for withdrawing the mixture from said vessel, means for moving the open end of said pipe upwardly through the mixture in the vessel to progressively vary the grade of material conducted to the grinding mechanism, and an indicator arranged to rise and fall in unison with the 50 open end of said pipe.

In testimony whereof, I have hereunto set my hand.

HALBERT K. HITCHCOCK.
